US0D1060229S

(12) **United States Design Patent** (10) **Patent No.:** **US D1,060,229 S**
(45) **Date of Patent:** **** Feb. 4, 2025**

(54) **CHARGING PILE**

(71) Applicant: **Guangdong Chongwei technology Co., LTD**, Yangjiang (CN)

(72) Inventor: **Caiyi Luo**, Yangchun (CN)

(73) Assignee: **Guangdong Chongwei technology Co., LTD**, Yangjiang (CN)

(**) Term: **15 Years**

(21) Appl. No.: **29/914,119**

(22) Filed: **Oct. 13, 2023**

(30) **Foreign Application Priority Data**

Sep. 5, 2023 (CN) 202330572710.1
